UNITED STATES PATENT OFFICE

2,611,251

NONPIERCING EARRING

Julius Guth, Rockville Centre, N. Y., assignor to
Sloan & Company, New York, N. Y., a corpora-
tion of New Jersey

Application December 23, 1950, Serial No. 202,457

1 Claim. (Cl. 63—14)

1. A non-piercing earring comprising

This invention relates to improvements in non-piercing earrings, such as ear clips or rings. Pursuant to the present invention, there is provided an article of jewelry which may be readily opened for application or removal and which tends to stay in closed position under torque spring tension. The article of jewelry made in accordance with the instant invention embodies novel features of construction and assembly which will become apparent as the description progresses, providing unique physical characteristics, and ease of manufacture, assembly and operation.

In the drawings:

Fig. 1 is an exploded plan view of the parts to be assembled to form an article of jewelry in accordance with the invention.

Fig. 2 is a plan view thereof, in partially assembled position.

Fig. 3 is a plan view showing a further step in the assembly operation.

Fig. 4 is a plan view of the completed article of jewelry.

Fig. 5 is an enlarged fragmentary sectional view, taken on line 5—5 of Fig. 4, and

Fig. 6 is a fragmentary enlarged plan view of the connector end of the arm 10, shown in Fig. 1.

As will become apparent on reference to the accompanying drawing and description below, the article of jewelry embodying the invention may be of any desired or convenient outline and relative proportions. It may, as shown in the drawings, to illustrate a practical application of the invention, be made to the final form of a generally circular, sectional ear clip or ring. As shown in Fig. 1, the parts used for the fabrication of that form of article embodying the invention comprise the arms 10, 11 having free contact ends 12, 13 to engage the ear of the wearer, and opposite open connector ends 14, 15 of substantially equal diameter, said open connector ends having recessed portions 19, 29. The free ends of the arms are adapted to have closing contact with each other when the article is completed and in operative position. To the same end, they are preferably provided with contact heads 16, 17, which may, as shown in Figs. 4 and 5, be disposed at an angle to the longitudinal axis of the arms 10, 11, and may be of complementary concave-convex form, to obtain a nesting effect indicated in Fig. 5. This specific outline of the contact heads may be varied, as may also their angular disposition with respect to the longitudinal axes of the arms 10, 11, or they may be entirely dispensed with, within the spirit and scope of the invention.

2

The connector end 15 of one of the arms—for example, arm 10—is provided with an extended rim end 18 of lesser diameter than that of the recessed end portion 19 in the other arm 11, adapted to be received in said recessed portion to swivelly connect the arms. A shouldered portion 25 is defined by the end 15 of the arm 10 at the point of connection of the extended rim 18 thereto. If desired, the arms 10, 11 may be made of hollow outline throughout, but that is not essential. A spring 20 is provided having loop ends 21, 22 to receive the pins 23, 24.

In the initial assembly of the parts above mentioned and shown in Fig. 1, the loop ends of the 15 spring are positioned interiorly of the arms 10, 11 through the connector ends thereof and the pins 23, 24 are inserted through apertures 23a, 23b, and 24a, 24b, in said arms 10, 11 (Fig. 2). The said apertures may be disposed 180° apart or at 20 any other desired arrangement which will permit the pins to pass through one aperture, through the spring end loop, and through the other aperture. The parts may be made of such proportions, as, for example, by tapering the pins 23, 24, and correspondingly forming the apertures to receive the same, that the pins may be wedged or force-fitted into said apertures to preclude 25 accidental displacement after assembly. One of the arms is then rotated relative to the other, as is indicated by the arrow R in Fig. 3, in a direction such as to set up a torque effect which will urge the free ends 12, 13 of the arms together, registering the contact ends thereof. Then the arms are brought together with the rim 18 of the arm 10 inserted within the recessed end portion 30 of the arm 11, and a third pin 30 is passed through an aperture 30a in the arm 11, through apertures 30c in the rim 18, through spring 20, through a second aperture 30d in the rim 18, and through the second aperture 30b in the arm 11, 35 precluding displacement of the connector ends 14, 15. The article will then be in the form shown in Fig. 4, the contact ends of arms 10, 11 being held engaged under the torque tension of the spring 20. The apertures 23a—23b, 24a—24b, 40 30a—30c—30d—30b are preferably transversely aligned, the pair of apertures 30a, 30b being disposed between the pair 23a, 23b and the terminus 45 or end 14 of arm 11.

The user may readily separate the contact ends 50 12, 13 for application of the clip to the ear of the user. The torque tension of the spring 20 will hold the article firmly in place until it is desired to remove the same, at which time the arms may be readily separated for that purpose.

Thus, the article of jewelry embodying the inven-

tion may be readily manufactured and assembled, and conveniently opened and closed by the user as occasion demands.

Having thus described my invention, what I claim as new and desire to secure by Letters Patent is:

An article of jewelry comprising substantially semicircular arms having inner and outer ends, the inner end portions of said arms being hollow and forming longitudinally extending pockets open at their outer ends, one arm having its inner end portion externally reduced and forming a sleeve rotatably fitting into the pocket of the other arm, said sleeve being formed in opposed portions with circumferentially extending slots, pins passing transversely through said arms and through inner end portions of the pockets, a helical spring extending longitudinally in said pockets and anchored at its ends to said pins, a pin mounted transversely through the inter- 20

fitting portions of said arms and passing through said slots and between convolutions of said spring and preventing separation of the arms and also limiting turning movement of the second arm about the sleeve, and heads at outer ends of said arms disposed for abutting side by side engagement with each other.

JULIUS GUTH.
